DESIGN FOR A CHAIR

Eric M. Johnson, Youngstown, Ohio, assignor to
The General Fireproofing Company, Youngstown, Ohio, a corporation of Ohio

Application August 11, 1937, Serial No. 71,005

Term of patent 14 years

To all whom it may concern:

Be it known that I, Eric M. Johnson, a citizen of the United States, residing at Youngstown, in the county of Mahoning and State of Ohio, have invented a new, original, and ornamental Design for a Chair, of which the following is a specification, reference being had to the accompanying drawing, forming part thereof.

Figures 1 and 2 are perspective views respectively of the front and rear of a chair embodying my new design.

I claim:

The ornamental design for a chair substantially as shown.

ERIC M. JOHNSON.
